F. C. STANKRAUFF

FURNACE

Filed Nov. 26, 1921

F.C. Stankrauff,

INVENTOR.

BY

BY
Geo. P. Kimmel.

ATTORNEY.

UNITED STATES PATENT OFFICE.

FRANK C. STANKRAUFF, OF DETROIT, MICHIGAN.

FURNACE.

Application filed November 26, 1921. Serial No. 517,841.

To all whom it may concern:

Be it known that I, FRANK C. STANKRAUFF, a citizen of the United States, residing at Detroit, in the county of Wayne and State of Michigan, have invented certain new and useful Improvements in Furnaces, of which the following is a specification.

This invention relates to hot air furnaces, 10 more particularly to the radiator drums of such devices, and has for one of its objects to improve the construction and increase the efficiency and utility of devices of this character.

15 Another object of the invention is to provide a device of this character whereby a direct or indirect draft may be caused to pass through the drum by simply manipulating a single pull rod.

20 With these and other objects in view the invention consists in certain novel features of construction as hereinafter shown and described and then specifically pointed out in the claims, and in the drawing illustrative of the preferred embodiment of the 25 invention—

Figure 1 is a transverse section of the improved radiator drum.

Fig. 2 is a vertical section of the structure 30 shown in Fig. 1.

A radiator drum in accordance with this invention, comprises a closed, annular casing or shell having arranged therein a plurality of circular partitions or members, positioned between the top and bottom of the 35 casing or shell, and mounted in spaced relation with respect to each other to provide an inner and an outer passageway and a flue spaced from the inner passageway.

40 The body portion of the casing or shell, is indicated at 10, which is tapered. 11 denotes the top and 12 the bottom of the casing or shell and which are formed integral with the body portion 10. Mounted 45 between the top 11, and bottom 12, is a plurality of circular partitions or members 13, 14 and 15, and which are arranged in spaced relation and with the member 15 spaced from the body portion 10. The member 13

50 provides a flue 16 which opens directly into the top of the combustion chamber of the furnace. The means to provide the combustion chamber is indicated at 19. The member 15, is spaced from the member 14 to form an inner passageway and the member 15 is spaced from the body portion 10

to form an outer passageway. The member 13, is spaced from the member 14, to form a hot air outlet space which surrounds the member 13, and the top 11, as well as the bottom 12, is formed with an opening, indicated at 43, so that the hot air passes through the space surrounding the member 13.

The member 16 in cross section is vertical, but the members 13, 14 are tapered, so that the space between the members 13 and 14 will gradually increase in width upwardly. The member 15, which is positioned between the member 14 and body portion 10, is provided with an enlarged opening 21, of a height equal to the height of the member 15, and diametrically opposite the opening 21, the member 15 has its lower portion provided with an opening 34. The opening 21 establishes communication between the inner passageway and the outer passageway, and the opening 34 when not closed establishes communication between the inner passageway and the outer passageway.

55 The member 14, as well as the member 13 is provided with an opening, and formed integral with the edges of said openings are vertically disposed lateral plates 20, which provide a passage 20' for establishing communication between the flue 16, and the inner passageway. The passageway 20' is in alignment with and extends toward the opening 34.

The means 19, which provide the combustion chamber of the furnace, has its upper 60 end formed with an inwardly arranged annular pocket 18, in which extends a depending flange 17, formed on the bottom 12, of the shell and which surrounds the lower open end of the flue 16. The upper end of the flue 16, is closed by the top 11. The flange 17, extends into the pocket 18, for connecting the radiator drum to the means 19, forming the combustion chamber of the furnace, but the bottom 12 is mounted on the top of said means 19, whereby the radiator drum is supported within the casing 40, of the furnace by the means 19.

105 Formed in the body portion 10, and in alignment with the passage 20', as well as the opening 34, is an opening 22, which is surrounded by a flange 23, secured to a flange 24 on the inner end of the smoke outlet flue 25, the latter is formed with a vertical flange surrounding an opening 26. Mounted on the flue 25 and surrounding the flange at the opening 26, is a smoke

discharge conducting flue 27. The outer end of the flue 25, is provided with a clean-out door 28. The bottom of the flue 25 extends upwardly at a slight inclination 5 and the said flue 25 is provided with flanges 41, which are secured to the casing or shell 40.

The body portion 10, is formed with an opening 29, which is in alignment with 10 the opening 21, and projecting from the body portion 10, as well as registering with the opening 29, is a flue 32, which constitutes a clean-out and is provided with a detachable closure 33. The flue 32 has 15 flanges 31, which are secured to flanges 30, on the body portion 10, and said flue 32 is furthermore provided with flanges 42 which are secured to the casing or shell 40.

20 The opening 34, is normally closed by a damper 35, which is carried on the inner end of a rod 36, slidably mounted in a guide lug 37, carried by the bottom 12 and the said rod projects outwardly through 25 the flue 25. The bottom 12, at the outer passageway, is formed with an opening 38 and communicating therewith is a downwardly extending flue or conducting pipe 39, which is adapted to communicate with the 30 ash pit, not shown, of the furnace, whereby dust and ashes directly from the interior of the drum may be conducted to the ash pit.

The body portion 10 is spaced from the 35 casing or shell 40, forming a passage for hot air, and as the body portion is secured to the flues 25 and 32, and as these latter are secured to the casing 40, the drum is not only supported from the combustion 40 chamber forming means 19, but also from the casing or shell 40.

From the foregoing construction, when the opening 34 is closed by the damper 35, the smoke and other products of combustion 45 pass through the passage 20 into the inner passageway traveling in both directions therethrough and discharge through the opening 21 into the outer passageway, thence in both directions through the outer 50 passageway to the outlet flue 25 and from there into the discharge flue 27. When the opening 34 is opened by shifting the damper 35 outwardly, the draft is directed from the flue 16, the passage 20', opening 55 34, through flue 25.

The providing of the body portion, as well as certain of the circular partitions tapered facilitates the casting of the drum, as well as renders the walls partially self-cleaning as the ashes, soot and like fine particles will not cling to the inclined walls but will fall by gravity therefrom.

The preferred embodiment of the invention is as hereinbefore described and illustrated in the drawing, but it will be under-

stood that changes in the details of construction can be had without departing from the principle of the invention or sacrificing any of its advantages and further such changes can be had which will 70 fall within the scope of the claims hereunto appended.

Having thus described the invention, what is claimed as new is:—

1. In a furnace a hollow annular radiator 75 element adapted to be mounted on the means providing the combustion chamber of the furnace and comprising a body portion having a top and bottom integral therewith and further including an inner, intermediate and outer spaced circular member interposed between and integral with said top and bottom thereby providing an outer passageway, an intermediate passageway and a centrally disposed flue spaced from the inner passageway and formed with a closed top and having its bottom opening directly into the top of the combustion chamber of the furnace, said top and bottom of said element formed with an opening to provide a hot air outlet passage between said inner and intermediate members, means for establishing communication between said flue and inner passageway, said outer member having diametrically opposed openings for establishing communication between said inner and outer passageways, an outlet flue leading from said outer passageway and in alignment with one of the openings in said outer member, and shiftable means for closing said last mentioned opening, said body portion and said inner and outer circular members being tapered. 95

2. In a furnace a hollow annular radiator 105 element adapted to be mounted on the means providing the combustion chamber of the furnace and comprising a body portion having a top and bottom integral therewith and further including an inner, intermediate and outer spaced circular member interposed between and integral with said top and bottom thereby providing an outer passageway, an intermediate passageway and a centrally disposed flue spaced from the inner passageway and formed with a closed top and having its bottom opening directly into the top of the combustion chamber of the furnace, said top and bottom of said element formed with an opening to provide a hot air outlet passage between said inner and intermediate members, 110

means for establishing communication between said flue and inner passageway, said outer member having diametrically opposed openings for establishing communication between said inner and outer passageways, an outlet flue leading from said outer passageway and in alignment with one of the openings in said outer member, shiftable means for closing said last mentioned opening, said body portion and said inner and 125

- outer circular members being tapered, and a clean-out flue opening into said outer passageway and arranged in alignment with the openings in the intermediate member.
- 5 3. In a furnace a hollow annular radiator element adapted to be mounted on the means providing the combustion chamber of the furnace and comprising a body portion having a top and bottom integral therewith and further including an inner, intermediate 40 and outer spaced circular member interposed between and integral with said top and bottom thereby providing an outer passageway and a centrally disposed flue spaced from the inner passageway and formed with a closed 45 top and having its bottom opening directly into the top of the combustion chamber of the furnace, said top and bottom of said element formed with an opening to provide a hot air outlet passage between said inner 50 and intermediate members, means for establishing communication between said flue and inner passageway, said outer member having diametrically opposed openings for establishing communication between said inner 55 and outer passageways, said openings arranged in alignment with said means, one of said openings being smaller than the other and arranged in proximity to said means, an outlet flue leading from said outer passageway and in alignment with and having its inner end in proximity to said smaller opening, and shiftable means for closing said 60 smaller opening.
- 35 4. In a furnace a hollow annular radiator element adapted to be mounted on the means providing the combustion chamber of the furnace and comprising a body portion having a top and bottom integral therewith and further including an inner, intermediate 40 and outer spaced circular member interposed between and integral with said top and bottom thereby providing an outer passageway and a centrally disposed flue spaced from the inner passageway and formed with a closed 45 top and having its bottom opening directly into the top of the combustion chamber of the furnace, said top and bottom of said element formed with an opening to provide a hot air outlet passage between said inner 50 and intermediate members, means for establishing communication between said flue and inner passageway, said outer member having diametrically opposed openings for establishing communication between said inner 55 and outer passageways, said openings arranged in alignment with said means, one of said openings being smaller than the other and arranged in proximity to said means, an outlet flue leading from said outer passageway and in alignment with and having its inner end in proximity to said smaller opening, and shiftable means for closing said 60 smaller opening.
- 35 4. In a furnace a hollow annular radiator

In testimony whereof, I affix my signature
hereto.

FRANK C. STANKRAUFF.
